UNITED STATES PATENT OFFICE

2,083,548

MATERIAL-BREAKING APPARATUS

Frank H. Armstrong, Chicago, Ill., assignor, by
mesne assignments, to Safety Mining Company,
Chicago, Ill., a corporation of Illinois

Application April 27, 1935, Serial No. 18,579
Renewed July 27, 1936

12 Claims.

(Cl. 102—6)

This invention relates to material-breaking apparatus, and more particularly to improvements in material-breaking shells of the type wherein highly compressed gas is employed as a material-breaking medium.

The most satisfactory form of post-charged shell in use prior to the present invention employs a chamber, in which a charge of highly compressed gas is stored, and control means for the retaining and venting of the charge, which includes a charge release valve means and differential-piston controlling means for the latter providing an area upon which pressure acts to close and hold closed the charge release valve means, and a smaller area subjected to storage chamber pressure and operative when the pressure acting on the larger area is released to open the charge release valve means and hold it open notwithstanding the sudden and very great reduction in storage chamber pressure which immediately ensues. This smaller area has a communication with the storage chamber controlled by means which permits ready passage of chamber pressure to the area, but precludes reverse flow, and thereby prevents a sudden drop in chamber pressure from also lowering the pressure on the smaller area and thereby permitting the less rapidly dropping pressure on the larger area momentarily reclosing the charge release valve means, with a resultant charge release in steps. The use of this essentially one-way connection between this smaller area and the storage chamber, however, results at times in delaying recharging until the pressure acting on the smaller area leaks away, and this difficulty my present invention avoids.

An object of my invention is to provide improved air-breaking apparatus not subject to the difficulty mentioned. Another object of this invention is to provide an improved material-breaking shell of the high pressure gas type wherein highly compressed gas is employed as a material-breaking medium. A further object is to provide an improved control means for such a shell for effecting release of the material-breaking charge from the shell. A still further object is to provide an improved differential valve release means for the charge of material-breaking pressure and having associated therewith improved control means for said release means. Still another object is to provide an improved vent means for the control chamber of the differential release means whereby when the control piston moves into its valve releasing position the side of the control piston which remains

under pressure is automatically connected to exhaust. These and other objects will hereinafter more fully appear in the course of the following description and as more particularly pointed out in the appended claims.

In the accompanying drawing there is shown for purposes of illustration one form which the invention may assume in practice.

In this drawing,—

Fig. 1 is a view in longitudinal section of the 10 illustrative embodiment of the improved material-breaking shell.

Fig. 2 is a view similar to Fig. 1, showing the control piston and valve assembly in released position.

In the drawing, A represents a material-breaking shell which is in many respects of the same general character as that disclosed in my copending application, Serial No. 718,175, filed March 30, 1934, and which is of the high pressure gas type wherein a highly compressed gas is employed as a material-breaking medium.

This shell comprises a tubular casing 1 having a chamber 2 for receiving a charge of high pressure gas, as for example highly compressed air; and threaded within the inner end of this casing is a discharge cap 3 having an axial discharge orifice 4 communicable with the pressure chamber 2 and connected by a series of generally radial, outwardly inclined discharge ports 5 with the shell exterior. Threadedly secured within the outer end of the casing 1 is a control cap 6 having a control chamber 7 containing a reciprocable control piston 8. The piston rod 9 of this piston extends inwardly within the pressure chamber 2 and has fixed to its inner extremity a pressure release valve 10 adapted to seat at 11 on the inner end of the discharge cap to prevent communication of the discharge orifice 4 with the pressure chamber. Positioned be-

tween the inner end of the control cap 6 and an internal annular shoulder 12 formed within the casing 1 is a heavy steel plate or disc 13 to which is secured a hat leather 14, surrounding and adapted to seal on the exterior surface of the valve rod 9, which passes therethrough. The piston 8 consists of a steel plunger 15 carrying a cup leather 16 held in position by a keeper 17 threaded on the valve rod 9. Threaded at 18 within the control cap 6 is a conduit 19 adapted to communicate with a suitable source of high pressure gas or to be vented; and this conduit is connected through an axial passage 20 with the control chamber 7 at the outer side of the control piston. A suitable check valve 21 with 55

check spring 22 is provided in the plunger 15 as a means for permitting the flow of high pressure gas from the control chamber 7 at the outer side of the control piston, through an axial passage 23 in the valve rod and communicating radial passages 24, into the main chamber 2 of the shell, but preventing flow in the reverse direction. A restricted radial passage 25 in the rod 9 extends from the axial passage 23 to the exterior of the valve rod, and is located at such a point that its outer end, when the piston and valve assembly is in the position shown in Fig. 1, communicates with the main chamber 2, and when the piston and valve assembly is in or close to the position shown in Fig. 2 communicates with the space between the inner side of the control piston and the disc 13, thereby connecting this space with the chamber 2, and so to atmosphere, noting that the valve 10 is then open.

The introduction of high pressure gas through the conduit 19 and axial passage 20 into the control chamber 7 at the outer side of the control piston results in axial movement of the valve 25 and plunger assembly to bring the valve 10 into firm sealing engagement with its seat 11 on the end of the discharge cap 3. At the same time the high pressure gas flows from the control chamber 7 past the check valve 21, and through passages 23, 24 into the main pressure chamber 2. It is important to note that as the pressure builds up in the main storage chamber 2, high pressure gas will pass from said main chamber along the valve rod 9 into the space at the inner side of the control piston and between said control piston and the metal plate 13, the hat leather 14 functioning as a check valve opening towards such space under these circumstances. In other words, gas under pressure from chamber 2 passes between the hat leather 14 and the valve rod 9 and into the space between the inner side of the control piston and the disc 13. It will be observed, however, that rapid reverse flow along the outside of the rod can not occur when the pressure in the main pressure chamber 2 falls, because of the check valve action of the hat leather which then takes place.

When a charge of high pressure gas of desired value has been introduced into the pressure chamber 2, discharge thereof is effected by cutting off the supply of high pressure gas to the conduit 19 and connecting the latter to atmosphere. Any suitable means, whether a three way valve, or more complex mechanism, may be used for this purpose. This venting results immediately in the lowering of the pressure in the control chamber 7 at the outer side of the control piston, and bearing in mind that the pressure of the gas trapped in the space at the inner side of the control piston between the latter and the disc 13, is substantially the same as that of the charge of pressure that was introduced into the main chamber 2, it will be apparent that the reduction of pressure in chamber 7 at the outer side of the control piston immediately results in axial movement of the valve and plunger assembly toward the left from the position shown in Fig. 1 to the position shown in Fig. 2 and in opening of valve 10. Note, of course, that the effective area of valve 10 within chamber 2 is less than the effective area of the right hand side of piston 8. The initial opening of the control valve 10 naturally results in an immediate and extremely rapid drop in pressure within the chamber 2, but in view of the very small size

of the passage 25, and the check valve action of the hat leather 14, the pressure trapped between the disc 13 and the inner side of the control piston will be sufficiently maintained to preclude the pressure in chamber 7 outside the piston 8 from reclosing valve 10. Thus, the gas in the space at the inner side of the control piston serves to move the valve and plunger assembly positively toward open position and to maintain it in that position until the charge has been effectually released. When the passage 25 is in the position shown in Fig. 2 with the control valve 10 in its wide open position, the pressure in the space at the inner side of the control piston vents to atmosphere through the charge chamber, discharge orifice 4, and discharge ports 5, but the size of passage 25, and the fact that it comes into communication with the space to the left of the hat leather only as valve 10 reaches substantially full open position, maintain the pressure in that space long enough to preclude "popping", i. e. serial discharges, due to momentary reclosings of valve 10. By the time the operator recovers the shell and is ready to recharge it, the pressure in the space mentioned will be vented so fully that the first readmission of pressure to chamber 7 through passage 20 will readily cause closure of valve 10 in readiness for a new charge.

It will be obvious that I have provided an improved shell, fully effective to prevent popping, and to insure full and free discharge to the point of its application of the charge of high pressure gas, but yet in readiness as soon as it can again be placed in a hole for recharging. If desired, the valve 10 may indeed be reclosed before positioning the shell in a new hole, by joining the shell when held with the discharge cap down.

While I have in this application specifically described one form which my invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In a material-breaking apparatus, a material-breaking shell having a chamber for receiving a charge of material-breaking pressure, discharge means for said chamber, a valve for controlling said discharge means, a differential piston for actuating said valve and for holding said valve closed, means for conducting pressure to said shell to act on the larger pressure area of said piston to hold said valve closed, valve means carried within the piston for conducting pressure past said piston to the pressure chamber to act on the opposed reduced area of said piston, said valve means closing automatically upon reverse in flow of the pressure, means for venting the larger area of the piston so that the pressure in the shell acting on the reduced piston area effects opening of the control valve, and means operative when said control valve is in its open position for venting the opposed reduced area of said piston to atmosphere.

2. In a material-breaking apparatus, a shell having a chamber for receiving a charge of material-breaking pressure, a discharge orifice therefor, a valve for closing said orifice, a differential piston for controlling said valve, means for introducing pressure into said shell, the pressure acting on the larger pressure area of the

5 piston to maintain said valve closed, the pressure flowing past the piston to the shell at the other side of the piston, means for venting the shell to reduce the pressure acting on the larger area of the piston so that the pressure in the shell 10 acting on the reduced piston area effects movement of the piston to open said valve, and means operative when said valve is in its open position for venting the reduced piston area to atmosphere.

10 3. A material-breaking apparatus comprising a source of compressed gas, a supply pipe extending therefrom, a material-breaking shell connected to said supply pipe, said shell embodying a differential valve controlling the release of compressed gas from said shell, said valve being actuated into closing position by the introduction of compressed gas into said shell through said supply pipe and being actuated to open position 15 when the flow of gas is reversed, means for cutting off the flow of gas from said source and reversing the flow of gas in said supply pipe, thereby effecting opening of said valve to release the compressed gas from said shell, and means operative when said valve is in open position for venting the gas acting to open said valve to atmosphere.

20 4. A material-breaking shell having a charge-receiving chamber with a discharge orifice and a control chamber, a valve in operative relation to said orifice for controlling the latter, means associated with said valve and positioned in said control chamber and responsive to the relative pressures in said charge-receiving chamber and control chamber for determining the position of said valve, and vent means operative when said valve is in open position for venting one end of said control chamber to atmosphere.

25 5. A material-breaking shell having a chamber adapted to receive a charge of highly compressed gas and a discharge opening through which said charge may escape, a differential valve within said chamber for controlling said discharge opening, means for establishing differential pressures calculated to open said valve, and means operative when said valve is in open position for venting the pressure acting to open said valve to atmosphere.

30 6. A material-breaking shell comprising a charge storage chamber, valve controlled means for releasing a charge from said chamber, and valve controlling means including means providing an area effective when subjected to pressure equal to or above charge pressure to maintain the charge releasing valve means closed, means providing an area effective when subjected to a pressure substantially equal to charge pressure and when said first mentioned area is vented, to effect opening and maintaining open 35 of the charge releasing valve means, means for venting said first mentioned area, and means automatically effective upon charge release to provide a retarded venting of said second mentioned area.

40 65 7. A material-breaking shell comprising a charge storage chamber, valve controlled means for releasing a charge from said chamber, and

valve controlling means including means providing an area effective when subjected to pressure equal to or above charge pressure to maintain the charge releasing valve means closed, means providing an area having normally only a 5 one-way communication with the charge storage chamber and effective when subjected to a pressure substantially equal to charge pressure and when said first mentioned area is vented, to effect opening and maintaining open of the charge 10 releasing valve means, means for venting said first mentioned area, and means automatically effective upon charge release to provide a retarded venting of said second mentioned area.

15 8. A material breaking shell having a chamber adapted to receive a charge of highly compressed gas and a discharge opening through which said charge may escape, a valve for controlling said discharge opening, means operative to open and hold open said valve, and means rendered operative by the opening movement of said valve for destroying the valve holding action of the first-mentioned means.

20 9. A material breaking shell having a chamber adapted to receive a charge of highly compressed gas and a discharge opening through which said charge may escape, charge releasing means for controlling said discharge opening, means operative to actuate said releasing means to effect release of said charge and to maintain said releasing 25 means in such condition, and means rendered operative by the actuation of said releasing means for slowly destroying the said maintaining action of the second-mentioned means.

30 10. A material breaking shell having a chamber adapted to receive a charge of highly compressed gas and a discharge opening through which said charge may escape, a valve for controlling said discharge opening, fluid operated means operative to open and hold open said valve, and means rendered operative by the full opening movement 40 of said valve for venting the fluid employed for operating said fluid operated means.

35 11. A material breaking shell having a chamber adapted to receive a charge of highly compressed gas and a discharge opening through which said charge may escape, a valve for controlling said discharge opening, differential pressure operated means for opening and holding open said valve, and means rendered operative by the full opening 50 movement of said valve for destroying the differential pressure condition which operates to hold the valve open.

45 12. A material breaking shell comprising a container adapted to receive a high pressure 55 charge and having a discharge orifice adjacent one end thereof, valve means for closing said orifice, releasable means adjacent the other end of said container for holding the valve means in said orifice, means to effect release of said 60 releasable means, means operative to open and hold open said valve means, and means rendered operative by the opening movement of said valve means for destroying the valve holding action of the valve opening means.
